United States Patent

Des. 240,195
Patented June 8, 1976

240,195

HANGER FOR FABRIC OR THE LIKE

Phillip Sperling, 3206 Coolidge Ave.,
Los Angeles, Calif. 90066

Filed Aug. 4, 1975, Ser. No. 601,531

Term of patent 14 years

Int. Cl. D8—08

U.S. CL. D8—249

FIG. 1

FIG. 3

FIG. 4

FIG. 5

FIG. 6

FIG. 1 is a perspective view of a hanger for fabric or the like showing my new design;

FIG. 2 is a side elevational view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a hanger for fabric or the like, substantially as shown.
